FEEDING APPARATUS FOR PULVERIZED MATERIAL.

1,402,184.

Specification of Letters Patent. Patented Jan. 3, 1922.

Application filed July 15, 1916. Serial No. 109,442.

To all whom it may concern:

Be it known that I, ARNOLD F. SINCLAIR, a citizen of the United States, residing at New York City, in the county of New York and State of New York, have invented certain new and useful Improvements in Feeding Apparatus for Pulverized Material, of which the following is a specification.

This invention relates to a device for feeding pulverized material, and is particularly adapted for feeding pulverized coal to a burner.

Great difficulty has been experienced in making use of pulverized coal as fuel, owing to the fact that it has the quality of flow to almost the same extent as a liquid. As a result of this quality, if the coal is fed by gravity or by means of any of the devices heretofore commonly used, there is constant danger that the coal will flow into the burner too fast, producing what is called "flooding."

I have devised an apparatus by means of which finely pulverized coal may be fed continuously at a uniform rate without any danger of too rapid flow or flooding. I have accomplished this by placing in the path of the pulverized coal, between the hopper in which it is stored and the place where it is burned, a rotating cylinder provided with interrupted helical grooves. The interrupted grooves constitute a series of pockets disposed in a helical line, so that as the cylinders rotate the coal carried in the grooves or pockets is deposited in the burner without material interruption and at a substantially uniform rate, as hereinafter explained in connection with the accompanying drawings, in which—

Fig. 1 is a longitudinal sectional elevation through the center of my feeding apparatus, and

Fig. 2 is a transverse sectional elevation taken on the center line of Fig. 1.

My feeding apparatus is surmounted by a hopper 1, of which only the lower portion is shown in the drawings. In this hopper the coal to be fed to the burner is placed. The opening at the bottom of the hopper admits to a cylindrical chamber 2 in the casing 3, in which is the grooved roller 4. This roller is keyed to an axle 5, which is journaled in the ends of the casing. The roller has a close running fit with the inner surface of the cylindrical casing 2, as near fluid-tight as possible.

As shown in the drawings, the roller 4

is provided with five interrupted helical grooves or series of pockets. Each groove extends almost the entire length of the roller and is divided into three pockets. The two ends of each groove are 90° of arc apart.

A channel 6 leads from the lower portion of the chamber 2 to a lower cylindrical chamber 7, in which is a roller 8, precisely like roller 4. The roller 8 is keyed upon the shaft 9. The shaft 9 is geared to the shaft 4 in such a way that the shaft 9 rotates somewhat more rapidly than the shaft 5. The power for rotating the rollers may be applied to either of these shafts.

An opening at the bottom of the cylindrical chamber 7 admits to a chute 10, which leads the coal into the injector 11, whence it is blown into the burning chamber by a blast of air entering the left-hand end of the injector.

In the operation of my apparatus the coal contained in the hopper 1 fills the grooves in the roller 4 as they pass across the aperture in the bottom of the hopper. As the roller 4 rotates, the contents of each groove is emptied into the channel 6. Owing to the helical shape and the arrangement of the grooves, the forward end of one groove passes over the channel 6 just before the rear end of the preceding groove passes away from the channel. This results in a continuous emptying of the coal into the channel. The fact that the grooves are interrupted prevents the coal from flowing from one end of a groove to the other and maintains an even distribution of the coal in each groove. In this way a uniform flow of coal is assured.

The coal poured into the channel 6 from the grooves of the roller 4 is uniformly distributed in the grooves and roller 8 as they pass under the channel and is emptied from these grooves into the chute 10, and so enters the burner 11 in a uniform and continuous flow.

The roller 8 is rotated more rapidly than the roller 4, in order to avoid any danger of the clogging of the channel 6.

While I prefer to use two rollers, as illustrated, as an extra precaution against the possibility of flooding, it should be noted that the device will operate and will feed the coal uniformly and continuously with the use of but a single grooved cylinder. The second cylinder is necessary only when the coal leaks by the first cylinder. Such

leaking can be prevented by a perfect fit of the first cylinder in its casing. But I prefer to use the second cylinder to eliminate the possibility of flooding should such leakage occur.

While I have described my device as used to feed pulverized coal to a burner, I wish it clearly understood that my invention, while very valuable for this purpose, is by no means limited to this use. The apparatus may advantageously be used whenever it is desirable to feed a pulverized material uniformly and continuously without danger of too rapid flow or flooding.

I claim:—

1. An apparatus for feeding pulverized material, comprising a casing, connected to the hopper in which the material is placed, and enclosing a cylindrical chamber connected at its top with said hopper, a second cylindrical chamber below said first mentioned cylindrical chamber, and a channel connecting said chambers; a roller having

helical grooves in said upper cylindrical chamber, means for rotating said roller; a second roller having helical grooves in said lower cylindrical chamber, and means for rotating said lower roller at a greater speed than said upper roller.

2. An apparatus for feeding pulverized material, comprising a casing, connected to the hopper in which the material is placed, and enclosing a cylindrical chamber connected at its top with said hopper, a second cylindrical chamber below said first mentioned cylindrical chamber, a channel connecting said chambers, and a chute connected with the lower portion of said lower cylindrical chamber; a roller having helical grooves in said upper cylindrical chamber, means for rotating said roller; a second roller having helical grooves in said lower cylindrical chamber, and means for rotating said lower roller at a greater speed than said upper roller.

ARNOLD F. SINCLAIR.
